COMBINED ANTIBIOTIC AND MYCOCIDE

Charles G. Shaw, deceased, late of Omemee, Ontario, Canada, by Walter Brackley Shaw, Marion Shaw, and Christina Isobell Connell, administrators, all of Omemee, Ontario, Canada, assignors, by mesne assignments, to Walter Brackley Shaw, Omemee, Ontario, Canada
Original application Aug. 23, 1957, Ser. No. 680,022.
Divided and this application Mar. 22, 1966, Ser. No. 536,952

14 Claims. (Cl. 167—58)

This is a division of co-pending application Serial No. 680,022, filed August 23, 1957, in the name of Charles G. Shaw.

This invention relates to a new and useful class of compounds which chemically combine an antibiotic substance with a mycoidal substance.

Specifically, the invention contemplates the reaction product of such antibiotic substances as Neomycin, Streptomycin, Terramycin, Aureomycin, and others with mycostatic and mycoidal agents such as the halide-substituted phenols, in order that the spectrum of the resultant antibiotic-mycostatic or antibiotic-mycoidal compound is greatly enhanced to include broader spectrums of mycoidal and bactericidal activity. Aureomycin and Terramycin are trade names for 7-chlortetracycline and 5-hydroxytetracycline respectively.

There has been a considerable amount of work accomplished in developing the phenol derivatives for use as fungicidal or mycostatic agents. Some of the phenols have a toxicity which makes them therapeutically valueless, but even of those mycoidal or mycostatic compounds which are non-toxic none appears to have a potent bactericidal spectrum in addition to the mycoidal spectrum.

Similarly, there is an enormous background of literature and information concerning antibiosis. It is stated by McVickar in "Therapy of Fungus Diseases," Sternburg and Newcomer, Little-Brown 1956: "None of the antibiotics employed so effectively in the treatment of bacterial and rickettsial infection is effective in the treatment of mycotic infections, systemic or superficial." In the same volume, Waksman refers to antibiotics active against fungi but inactive against bacteria, and with respect to their activity against fungi, highly selective in their actions against different fungi. These spectrum deficiencies are notable in all antibiotics, even those having a "fringe" action against either bacteria or fungi. There appears to be no prior art relating to the actual combination in one molecule of a compound effective in a wide spectrum as both an antibiotic and a mycostatic agent.

It is important to emphasize that the compounds contemplated in the present invention are those wherein a mycostatic agent and the antibiotic agent are chemically reacted together to form a single compound effective in a broad spectrum, wherein there is a chemical bond between the two agents. There may be known methods of medical treatment involving the simultaneous application to a certain body area of a mycostatic agent and an antibiotic agent, but this is not within the scope of the invention and as indicated above there is no known case where a mycostatic agent and an antibiotic agent have been chemically compounded for medical or other use.

The advantages of a complex compound of a mycostatic and antibiotic agent are many fold. One important advantage is in the control of solubility and diffusion rates. It is a known fact that the effectiveness of a mycostatic and antibiotic agent is partly dependent on the rate at which the compound diffuses into the body

tissues. Depending on the nature of the area being treated with the treatment desired, various means are employed to vary the rate of diffusion of the compound into the tissues. If, for instance, to a certain area one wishes to apply separately or in mixture form an antibiotic agent and a mycostatic agent, different solubilities of the two agents would affect the diffusion rates of the two agents and the two components would not remain in the infected area in the desired proportions. There are many physio-chemical properties of the components other than their solubilities which would similarly affect application. Chemically combining the antibiotic and mycostatic agents would give them common physio-chemical properties including a common diffusion rate and would considerably simplify the control of the application technique.

A second advantage linked with the above is the ability in the complex compound to control the relative bactericidal and mycoidal effectiveness. Briefly, if it were desirable to achieve an application to the infected area of a mycoidal agent and bactericidal agent in the ratio of one to two, this could easily be facilitated by the method herein described, by simply chemically combining the desired components in the desired ratio. By means of the chemical link, one is assured of the continued maintenance of this ratio to the infected area.

A further advantage may be seen in what is termed a synergistic effect.

A further advantage is apparent in the fact that a new means is available for therapeutically using the highly toxic mycostatic agents such as pentachlorophenol by means of this bond with an antibiotic, a means which permits even greater concentrations of the mycostatic agent with less toxicity than previously obtained by buffering techniques or like means of toxicity control.

Having briefly outlined the concepts and advantages of the invention, it is thus a primary object to provide a new chemical compound having an antibiotic component, wherein the compound will have a considerably extended effective mycoidal spectrum.

It is further an object to provide means in a single chemical compound simultaneously effective against both bacterial and mycoorganisms wherein the relative bactericidal and mycoidal potencies or spectrum can be varied or adjusted depending on the treatment desired.

It is further an object to provide a means for controlling the pH of the compound, and solubility of the compound, and for controlling and equalizing the diffusion rates of the components and for minimizing toxic effect or sensitivity of certain components of the compound.

It is another object to provide a compound having a more effective control of the pathogenic fungi and the bacteria than would be obtainable by the separate but simultaneous use of the individual components of the compound.

The invention has for another object, the provision of a compound for therapeutic application, which would also be effective against food spoilage and plant diseases, and as an animal food supplement.

Further objects and advantages will become apparent from the following description and examples of the invention.

Microbial activity may be divided into many classifications, by the genus of the involved organism, or the species, or mutation, or pleomorphic form, etc. Various arts ascribe certain organisms into varying categories and all arts related to the use or control of micro-organisms are concerned with the relative activity or control of many genera and species. To illustrate, but not in a definitive sense, the following classification will suffice to arrange pathogenic organisms from bacteria to

fungi in a spectrum serving as a guide in designating therapeutic control—viruses, Rickettsia, Gram-negative bacteria, Gram-positive bacteria, Coccidae, Mycobacteria, Actinomycetes, Myco-pathogens, Lepto-thricyia, Algae and Animalculae.

There are several other borderline species unknown in the literature termed Cata-thricyia and complex mycotic forms, now undergoing investigation in my laboratory in connection with dental lesions and those under investigation by Dr. J. W. Papez at Columbia State Hospital, Columbus, Ohio, and Dr. Irene Diller, at the Institute of Cancer Research in Philadelphia. From studies of the microbiota of the oral cavity, these borderline species appear to be many genera and species of questionable identity, some apparently pathogenic in form, in chronically granulomatous conditions and in other forms of lesions. They include the extremely fine filamentous form which I have called Cata-thrix, and which is now under study in dark field and electron microscopy. It is of a fungus like nature and appears to have pleomorphic spore forms and to segment into virus like free forms. Certain species of organisms are associated with the tongue coating which is a very malodorous and disagreeable feature in the syndrome of such diseases as virus hepatitis—these and certain others which appear to be pleomorphic forms of Lepto-thricia are readily controlled by therapeutics resulting from this compound. Antibiotics and chemotherapeutics of the broadest possible action are desirable, as many diseases evidence symbiotic and complicated infections.

Those involving bacteria and myco-pathogens are frequently encountered. An ideal therapeutic would be active against all pathogenic organisms. None has been discovered, though a constantly increasing number of antibiotics provide a multiplicity of effective therapeutics over quite broad portions of the pathogenic spectrum.

The known antibiotics, originating from the metabolism of micro-organisms, which are effective as bactericides and/or fungicides, are too varied and obscure in chemical constitution to permit complete categorical classification. However, generally they are in the nature of organic acids or bases and/or other complexes capable of combining with acidic or basic radicals to form salts. All such antibiotic salts are within the scope of this invention.

In the art there is also considerable reference to mycoidal organic chemical compounds such as the halogen-substituted products of phenol and halogen-substituted compounds of benzoquinone, hydroquinone, and phloroglucinol. There are further many other aromatic halogen-substituted compounds which, either as bare acids, or their metallic or organic salts have marked fungicidal or mycostatic properties. Many other aromatic derivatives of benzene can be formulated into new and useful mycostatic chemotherapeutic agents but none of the agents disclose a broad spectrum of bactericidal properties. It may be sufficient herein to emphasize that many of these halogen-substituted compounds of the various phenols are quite toxic and produce highly objectionable sensory reactions requiring careful solubility control, pH control and limited concentration of the effective ingredient. It is important, however, to note that the strong acidic properties of the more highly saturated substituted products of the phenols make them highly desirable in the preparation of the above mentioned antibiotic-mycocide complexes. They provide an extremely stable chemical bond, either directly with an antibiotic base or indirectly with an acidic antibiotic through a di- or tri-valent base such as calcium or bismuth. The strength of this bond between the antibiotic substance and the mycocide complex should be such that it cannot be broken under the conditions in which these new complex compounds may be used and in many instances a very delicate balance of the pH inherent in its solutions, should be provided without recourse to supplementary buffering.

The substituted mycoidal phenol derivatives can also

be reacted with the antibiotics through the linkage of a polybasic strong acid, or by forming a mixed crystal complex with a polybasic acid. These concepts are disclosed in the examples which follow.

5 It should merely be emphasized that all mycostatic agents including the halide substituted benzene derivatives, and means for linking said agents with the antibiotics are within the scope of this invention.

In all of the antibiotic-mycocide compounds disclosed in the examples which follow and in all those within the scope of the invention, there is a chemical linkage or bond between the mycoidal agent and the antibiotic. This bond may involve the presence of a polybasic acid or salt, or a crystal complex. Generally the antibiotic is a multi-valent base or acid, or salt having an affinity or ability to react with one or several molecules of the mycoidal agents. By controlling the reaction, one can leave available valences or linkages on the antibiotic molecule or elsewhere in the resultant molecule for reaction with acidic or basic molecules to control the pH of the final compound. For instance, Neomycin has an affinity or ability to react with from one to six molecules of pentachlorophenol, replacing the hydrogen ion of the hydroxyl group of the benzene acid. If the reaction is controlled such that only four of the six valences of Neomycin are utilized, two active valences still remain for reaction with acidic radicals to further control or adjust the pH to a desired level.

30 The following examples illustrate the concepts of the invention and representative means for compounding the therapeutic agents contemplated.

It should be noted that even though several of the examples specify carrier agents or means of application, the invention is not to be limited to such agents or means.

35 In these examples, and in examples where no specific carrier or means of application is indicated, it will be understood that the antibiotic-mycocide chemical compounds can be compounded into solutions, ointments, dusting powders, dips, sprays, etc., there being a wide choice of vehicles and solvents well known in the arts, to accommodate the varying physio-chemical properties including solubility of the many antibiotic-mycoidal chemical components and further to affect and control diffusion rates depending on the desired application and nature of treatment. Dispersion on kaolin, talc, and other suitable vehicle and solvents are obvious.

Example I.—Neomycin hexa-pentachlorophenate

50 Pentachlorophenol is a mycostatic agent which has been shown to be highly effective against many fungi. Neomycin, a known antibiotic, when chemically combined with pentachlorophenol produces a compound according to the invention which is highly effective against a wide spectrum of myco-organisms and bacteria.

55 The highly basic properties of the neomycin base permit it to react with six molecules of hydrochloric acid to produce a Neomycin chloride salt at about 5.2 pH, the molecular weight of Neomycin being calculated as 774.8 60 and the substance employed being approximately 98% pure. Similarly, Neomycin base can be reacted with six molecules of pentachlorophenol to form Neomycin hexa-pentachlorophenate, a salt having a pH between 6.0 and 5.2 which is comparable with the hexa-chloride. It is not necessary to utilize the full combining power of the Neomycin to react with the mycostatic agent. Four of the six valences of the Neomycin base may be utilized to chemically combine with only four acidic pentachlorophenol molecules to produce an effective relative proportion. Two active valences will remain for more or less acidic acid radicals adjusting the final pH of the whole compound to a desirable level. The possibilities of pH adjustment and control of the relative mycostatic and bacteriastic potencies are apparent.

Neomycin hexa-pentachlorophenate is prepared in the following manner:

	Grams
Pure Neomycin base	1.3100
Pentachlorophenol	2.6392

¹ Dissolved in 4.0 cc. water.

² Dissolved in 20.0 cc. 95% ethyl-alcohol.

The Neomycin and pentachlorophenol solutions are mixed by pouring the pentachlorophenol solution into the Neomycin base solution. The two react at room temperature to form Neomycin hexa-pentachlorophenate. To this is added 60 ccs. of Eugenol.

The preparation is useful in root canal therapy and the treatment of periodontal pockets with dressings and topical applicaitons. The preparation may also be used in a well-known periodontal pack comprising zinc oxide, rosin, and tannic acid.

Neomycin hexa-pentachlorophenate has bactericidal properties corresponding with those of the Neomycin sulfate or chloride salt, including activity upon *Staphylococcus albus* and *Staphylococcus aureus*, *Streptococcus fecalis* and *Mycobacterium tuberculosis*, and mycocidal properties with *Candida albicans* and many other fungi, as also with such organisms as *Leptostricia* and similar species associated with gingival lesions and tongue coatings.

The compound is highly effective against both bacteria and fungi and in addition against borderline species known in the art. It should be noted further that the individual spectra of both of the components is in no way adversely affected, and that the toxicity of the pentachlorophenol is practically eliminated.

Example II.—Streptomycin-tri-pentachlorophenate

Pentachlorophenol, M.W. 266.35, combines with 1 mol. NaOH 40.01 gms. to produce the sodium salt, M.W. 288.34. A $\frac{1}{2}$ mol. solution is prepared of sodium pentachlorophenate in water. A $\frac{1}{2}$ mol. solution of silver nitrate, M.W. 169.89, also in water, is prepared, and equivalents of the two above solutions are mixed together with stirring. The resulting reaction produces a silver-pentachlorophenol salt. Due to the nature of the bond of the substituted chlorine in the pentachlorophenol molecule, there is no interaction between the silver nitrate and the substituted chlorine, but merely a substitution of the silver ions for the sodium ions. The salt is alcohol soluble.

Streptomycin hydrochloride, according to Merck, p. 907, Merck Index, Sixth Edition, has the working formula $C_{21}H_{39}N_7O_{12} \cdot 3HCl$. All three of the chloride ions are available to react with the silver-pentachlor salt, thus providing with 1 mol. of Streptomycin base, valency for 3 mols. of pentachlorophenol.

The silver-pentachlorophenate is dissolved in alcohol and a Streptomycin hydrochloride water solution is mixed with it by stirring.

	Grams
Silver pentachlorophenate	¹ 1119.66
Streptomycin tri-hydrochloride	² 690.003

¹ Dissolved in alcohol.

² Dissolved in water.

The reaction between the silver and the chloride occurs at room temperature and progresses quickly such that no heat or catalyst is necessary. The Streptomycin tri-pentachlorophenate (net weight 1380.63 grams) remains in solution in the alcohol water mixture and the cloudy silver chloride precipitates and is removed. The solution can be dehydrated or concentrated for storage or application. The resultant antibiotic-mycostatic compound is fully effective against the known spectra of the components, and in many instances the spectrum is enhanced.

Example III.—Di-hydro Streptomycin tri-pentachlorophenate

This reaction can be carried out with di-hydro Streptomycin sulphate as follows:

BaCl ₂ H ₂ O	gms	244.31
Sodium pentachlorophenate ($\frac{1}{2}$ mol. solution)	gms	532.70

The typical Barium reaction results are:

Barium (pentachlorophenate) ₂	gms	670.06

The precipitate is insoluble in water but will dissolve in alcohol.

Di-hydro Streptomycin base (calculated from the sulfate salt) dissolved in water, 1 mol.	gms	583.59
Ba (pentachlorophenol) ₂ dissolved in alcohol, $\frac{1}{2}$ mols.	gms	1005.09

This reaction is carried out at room temperature and barium sulfate precipitates and is removed.

The ordinary mycostatic and bacteriostatic spectrum of neither the pentachlorophenol nor the antibiotic is damaged by the reaction; in fact the spectrum of both is enhanced. The mycocidal phase of Streptomycin is enhanced sufficiently to be extraordinarily active against Myco-bacillus tuberculosis as well as other fungi and bacteria.

Either of the Streptomycin compounds can be easily mixed with various carrying agents for application as indicated above.

Example IV.—Phlortetracycline mono-pentachlorophenate

Aureomycin, termed chlortetracycline hydrochloride, has a chloride ion available for reaction with the acidic mycostatic agent.

	M.W.
Aureomycin hydrochloride	543.000
is capable of reacting with	
Silver pentachlorophenate	373.22
to produce	
Aureomycin mono-pentachlorophenate	773.35

The product is not stable in aqueous solution over long periods. It is also bland but very effective on organisms associated with certain periodontal disease conditions and on dermal mycosis. It has a virus and rickettsial inhibitory capacity valuable in treating infections which frequently complicate oral septic conditions.

Example V.—Tetracycline mono-pentachlorophenate

Similarly tetracycline hydrochloride, M.W. 506.535, is capable of reacting with silver-pentachlorophenate, M.W. 373.22, to produce tetracycline mono-pentachlorophenate, M.W. 763.885.

This product is also bland and very effective on organisms associated with certain periodontal disease conditions and on dermal mycosis. The spectrum of neither component is adversely affected by the chemical bond and is probably enhanced in each instance. There is also definitely produced a virus and rickettsial inhibitory capacity, valuable in treating oral infections.

An acid such as pentachlorophenol, considered much weaker than hydrochloric acid, nevertheless reacts with the six valences of Neomycin base in a manner surprisingly similar to the reaction of the base with hydrochloric acid. The pH of many phases of their neutralization curves is practically coincidental. In this sense, the pentachlorophenate ion has an effective affinity similar to the sulphate or chloride ion.

Many of the halo-substituted aromatic mycostatic agents less saturated and acidic in nature are incapable of effecting a permanent bond with an antibiotic base.

For instance, 2,4,6-trichlorophenol with a Ka. of

2.6×10^{-8} is incapable of neutralizing the basic properties of Neomycin base, and yet trichlorophenol and other similar mycostatic compounds have highly desirable and effective mycostatic properties.

It has been found, however, that any of the weak acidic halide substituted phenols can be reacted with a highly acidic mineral acid such as sulphuric and phosphoric acid to combine it with the first hydrogen radical of the mineral acid, thus leaving the remaining acidic ions of the mineral acid to form a tenacious bond with a basic antibiotic substance such as Neomycin.

This provides an alternative and very important means for linking the highly saturated mycostatic compounds with an antibiotic. The following example is directed toward the utilization of pentachlorophenol, but it is to be understood that the same principles can be applied as a means for linking the above mentioned less highly saturated acidic mycostatic substances with the antibiotics. Furthermore, the following example utilized acetylsalicylic acid but it is to be understood that any of the mineral polybasic acids can be used.

Example VI.—Complex of Neomycin and salicylic acid pentachlorophenolate

It was desired to combine pentachlorophenol with Neomycin using acetylsalicylic acid (aspirin) as the intermediate bonding agent. Acetylsalicylic acid was chosen because of its strong acidic properties and its properties as a medicament. In the reaction, pentachlorophenol apparently displaced the acetyl group, and the components were linked at the hydroxyl position of the salicylic acid. The reaction was carried out by dissolving pentachlorophenol and aspirin, one mol. each, in small amounts of ethylene di-chloride and with a small amount of hydrochloric acid to activate the mix, the mixture then being heated to about 89° to 127° C.

Gms.

Pentachlorophenol	26.635
Acetylsalicylic acid	18.015
were dissolved in ethylene di-chloride and hydrochloric acid and heated resulting in a stable clear solution of	
Salicylic acid pentachlorophenolate	40.346

The following reaction is believed to have occurred.

The carboxylic group is probably left free to react with the Neomycin base. In any event, it is quite certain that the phenol does not substitute into the aromatic ring of the salicylic acid. Accordingly, it is appropriate to identify the reaction product as a phenolate.

The salicylic acid pentachlorophenolate was then reacted with Neomycin base in the ratio of 5 mols. to 1 mol. respectively.

Salicylic acid pentachlorophenolate	gms.	.1606
Dissolved in non-ionic Tween (Merck)	gms.	.15
H ₂ O	ccs.	10
Alcohol (95%)	ccs.	40

To this solution was added:

Neomycin base	gms.	.0775
H ₂ O	ccs.	25

The resultant compound was diluted in 200 ccs. of water, giving a pH of 6.21, and was satisfactory for use in a topical dermal dressing.

Since the aspirin-pentachlorophenolate is tender, it is preferable to pour the base slowly into the acidic solution to prevent any reaction which might rupture the phenol-salicylic bond.

As indicated above, the pH of the final compound can be adjusted by further linking of acidic ions to the antibiotic base. It is desirable, however, that the acidic ions be of not too great relative acidic strength. For example, sulfate and chloride ions would tend to rupture the phenol-salicylic bond, but an acid of equivalent strength to the salicylic acid can be used.

One can appreciate the variety of compounds obtainable with the reactions described above. For instance, p-chlorophenol having a K_a of 4.1×10^{-10} is relatively basic, and would not be expected to combine in the hydroxyl position of salicylic acid. However, o-phthalic acid and terephthalic acid have a sufficient spread with p-chlorophenol, in ionization, to form tenable bonds with it. Many similar compound acids and acid salts possessing high fungicidal properties can thus be formed and utilized to fall within the scope of the invention.

Example VII.—Buffered Neomycin tri-penta-chlorophenolate

As an example of the pH buffering aspect of the invention, Neomycin tri-pentachlorophenolate can be formed to leave available three valences of the Neomycin base for reaction with a buffering acid or acid salt.

30	Neomycin base	gms.	.0775
	Pentachlorophenol	gms.	.0799
	Water	ccs.	5
	Alcohol (95%)	ccs.	5

The pentachlorophenol is added to the Neomycin base solution resulting in the tri-pentachlorophenol base with a pH of about 7.5. To this solution is added .5 cc. of .5 NHCl which forms a temporary precipitate and .99 cc. of .5 NHCl progressively thereafter to occupy the remaining 3 valences of Neomycin with the chloride ion. The resultant solution has a pH about 5.5. Three mols. of $\frac{1}{2}$ neutralized o-phthalic acid or p-phthalic acid could be reacted with the above salt to depress the pH to between 6 and 5.2, equivalent to the hexa-pentachloride of Example I.

Similarly, many other compound variations such as Neomycin - mono - pentachlorophenolate - pentasulfate or pentachloride can be formed.

Example VIII.—Non-alcoholic nasal spray and topical dermal dressing

50	Acetylsalicylic acid	gms.	1.8015
	Pentachlorophenol	gms.	2.6635

The two above components were dissolved in acetone and the solution heated to from 120° F. to 150° F. to evaporate the acetone. The residual mass was a crystalline mixture of one mol. each of pentachlorophenol and acetyl-salicylic acid (molecular weight 446.50), and was not a molecular compound as illustrated in Example VI. The nature of the crystal was uncertain, but there was no displacement of the acetyl group in the aspirin.

The mixed aspirin pentachlorophenol crystal was then incorporated into a nasal spray or topical dermal dressing in the following manner.

55	Mixed crystal of aspirin and pentachlorophenol	gms.	.1339
60	Menthol	gms.	.0781
	Non-ionic Tween (Merck)	gms.	7.5

The above was dissolved in a small amount of water, about 25 cc., into which the Neomycin base was added and stirred at room temperature.

98% pure Neomycin base gms .775
Dissolved in water cc 10

The above formula is based on a proportion of 3 mols. each of aspirin and pentachlorophenol to 1 mol. of Neomycin base. It is apparent that all 6 molecules of the aspirin and pentachlorophenol are free to react and do react with the Neomycin. There is in this manner provided a means of simultaneously effecting the mycostatic-antibiotic reaction and adjusting the pH of the resultant solution. It should be noted that any number of appropriate acids or salts can be similarly incorporated into the resultant compound for pH control.

The above solution when diluted with 50 to 100 cc. of water to a desired concentration, results in medicament having a quite bland sensory reaction in application and a bacteriostatic and mycostatic spectrum broadly equivalent to Neomycin tri-pentachlorophenate.

Example IX

The acidic antibiotics such as penicillin can be combined with calcium or bismuth or any strong bi- or trivalent base to form a basic salt. The remaining valences of the base can then be used to link the penicillin with the mycocidal acidic compound.

This can also be done by reacting 1 mol. of calcium with 1 mol. of pentachlorophenol to form a basic salt which can then be reacted with penicillin.

Example X

Tetrachloroquinone, being an oxygen donor, will combine with the antibiotic base, but apparently attacks it by oxidation. By using various proportions of tetrachloro-quinone with tetrachloroquinone, the well known quinhydrone reaction takes place, thus modifying the oxidation tendency, and a stable bond can be formed between the base and the mycostatic substance.

I claim:

1. A method of medical treatment comprising topically applying to tissue a complex of an antibiotic selected from the group consisting of Streptomycin, di-hydro Streptomycin, Neomycin, tetracycline, oxytetracycline, chlortetracycline, and a basic salt of penicillin complexed with a halogenated phenol having the formula:

wherein R is selected from the group consisting of hydrogen, halogen and hydroxy and wherein at least one R radical is always halogen.

2. A method according to claim 1 wherein the antibiotic is selected from the group consisting of calcium and bismuth salts of penicillin.

3. A method according to claim 1 wherein the antibiotic is selected from the group consisting of acid salts of tetracycline, oxytetracycline and chlortetracycline.

4. A method according to claim 1 wherein the antibiotic is selected from the group consisting of mineral acid salts of tetracycline, oxytetracycline and chlortetracycline.

5. A method according to claim 1 wherein the antibiotic is selected from the group consisting of Streptomycin and dihydro Streptomycin.

6. A method according to claim 1 wherein the antibiotic is Neomycin.

7. A method according to claim 1 wherein the antibiotic is tetracycline.

8. A method according to claim 1 wherein the antibiotic is oxytetracycline.

9. A method according to claim 1 wherein the antibiotic is chlortetracycline.

10. A method according to claim 1 wherein the complex is Neomycin hexapentachlorophenate.

11. A method according to claim 1 wherein the complex is Neomycin triphenyltachlorophenate.

12. A method according to claim 1 wherein the complex is tetracycline monopentachlorophenate.

13. A method according to claim 1 wherein the complex is chlortetracycline monopentachlorophenate.

14. A method according to claim 1 wherein the halogenated phenol is pentachlorophenol.
